GRINDING MACHINE

Erwin G. Roehm, Norwood, Ohio, assignor to The Cincinnati Milling Machine Co., Cincinnati, Ohio, a corporation of Ohio

Application July 9, 1953, Serial No. 366,947

9 Claims. (Cl. 51—100)

This invention relates to improvements in grinding machines, and relates particularly to a novel and improved machine for performance of form grinding operations.

One of the principal objects of the present invention is the provision of an improved machine, particularly adapted for the grinding of contours or irregular shapes in correspondence with the dictates of a controlling pattern or master.

A further object of the invention is the provision of an improved multiple spindle grinding machine capable of utilization for simultaneously producing a number of duplicate work pieces under control of a pattern which includes means for facilitating the several relative movements of the work pieces and grinding wheels for minimizing the power required for shifting of the parts and for increasing the sensitivity and consequent accuracy of operation of the machine.

A further object of the invention is the provision of a machine tool embodying improved means for supporting a tool spindle for universal movement in a plane with respect to the work piece to be operated upon and in which the various movements in the cutting plane as determined by a tool on the spindle may be readily automatically controlled.

An additional object of the invention is the provision in a machine as above set forth of simplified mechanism for supporting the weight of the spindle carrier and associate parts to facilitate their ready movement and adjustment.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Figure 1 is a front elevation of a machine embodying the principles of the present invention.

Figure 2 is a side elevation with a portion of the grinder casing broken away.

Figure 3 is a plan view of the machine.

Figure 4 is a view partially in elevation and partially in section on the line 4—4 of Figure 3, and

Figure 5 is a diagrammatic view of the hydraulic control circuit for the machine.

Figure 6 is a horizontal section of the pattern on line 6—6 of Figure 1.

Figure 7 is a horizontal section of a work piece on line 7—7 of Figure 1.

In the drawings the numeral 10 designates the bed of a grinding machine having rising at the rear the hollow upstanding column 11 provided with ways 12 for the vertically movable slide 13 which may be moved up and down on the face of the column by any suitable adjusting mechanism. One mechanism for this purpose is particularly illustrated in Figures 2 and 4. Mounted in the column are a pair of spindles 14 and 15 on which are rotatably supported the worm gears 16 and 17 meshing with the worms 18 and 19 on the slide adjusting shaft 20. This shaft is provided with a beveled gear 21, meshing with the bevel gear 22 on shaft 23 which extends forwardly from the column 11 in the housing 24. A pilot wheel 25 is loosely mounted on the forward end of the shaft and can be coupled with the shaft by the clutch structure indicated at 26. Rotation of the pilot wheel in one direction or the other will rotate the worm and thus the gears 16 and 17. Connected with these gears are the rock arms

2

27 and 28 connected by the links 29 and 30 which are pivoted to the slide 13. Rocking movement of the arms 27 and 28 serves incrementally to raise or lower the slide.

At its ends the slide is provided with the trunnions 31 and 32 on which are pivoted the toggle links 33 and 34. A second pair of links 35 and 36 are pivoted to the links 33 and 34 by the pins 35 and 36 at one end, and their opposite ends are connected by the pivots 39 and 40 to the tool carrier plate 41. A rod 42 connects the pivots 35 and 36 to maintain the same in preselected spacing so that the combination of the several toggle links and rod 42 form a parallel motion connection intervening the vertical movable slide 13 and the tool carrier plate 41.

Mounted on the tool carrier plate 41 are a plurality of brackets 43, each supporting a self-contained motor driven spindle unit comprising a motor 44 for driving spindle 45 carrying the small diameter grinding wheel 46 for operation on a work piece 47 secured in position on the bed of the machine as by the clamp screw 48.

To provide for free vertical adjusting movement of the slide 13 and at the same time effect a counterbalancing of the slide 13 and the tool carrier 41 so that the parts may readily be adjusted in unison and the toggle links serve primarily as a positioning support relieved of the main portion of the weight of the carrier 41 and associate parts, use is made of the counterbalance weights 49. These have been illustrated as two in number contained within the hollow column 11 and each provided with a pulley 50 around which is passed a supporting cable 51 having one end extending over the idlers 52 and 53 and secured in the eye 54 carried by the slide 13. The opposite end of the cable 51 extends over the idler 55 and idler 56 at the front of the column extension 57 and is, in turn, secured to the eye 58 carried by plate 41. As shown, there are employed two sets of these cables and idlers suitably spaced apart as respects the direction of longitudinal extent of the vertical slide and the spindle carrier so that they exert a balancing or stabilizing effect as to the horizontal position of the parts, preventing binding of the slide on the ways 12 and at the same time exert an equalized upward force on corresponding portions of the slide 13 and carrier 41. By this construction the carrier 41 is supported for relatively free swinging movement by the linkages 33, 37, and 34, 38 and is capable of being easily moved in a forward and back direction, varying the separation between the members 41 and 13, or in a longitudinal direction parallel with the member 13 or in any combination of such movements so that the spindles 45 may be shifted in an ambulatory path about the respective work pieces 47.

In the present instance the work pieces have been shown as turbine blades which may be of carbide or other difficult to machine material in which it is necessary that the various pieces be accurately produced as duplicates to very fine tolerances. To enable the movements of the spindle carrier to be accurately controlled, there is mounted on the carrier a pattern holder bracket supporting the pattern 60 which in the particular arrangement shown is indicated as being mounted in a reverse or opposite direction from the mounting of the work piece 47, thus providing a pattern of opposite hand to the work pieces. Mounted on the bed 10 for cooperation with the pattern is a 360 degree tracer head unit 61, which may be of the type shown in detail in Patent 2,332,533, including a tracer finger 62 engageable with the pattern 60. This head is preferably carried by a slide 63 on the bed, permitting longitudinal adjustment to insure proper contact between the tracer finger and pattern when the several work pieces are correspondingly engaged by the cutters or grinding wheels 46. This tracer unit is of standard conventional construction in which the intermediately pivoted tracer spindle 64 reacts on a valve 65 controlling rotation of motor 66 which, through the diagrammatically indicated drive connection 67, operates the rate and direction control cam 68. This cam engages a first plunger 69 on the reversing valve 70 in valve casing 71. It also engages the plunger 72 of the reversing valve 73 in casing 74.

As is conventional, these plungers are phased at a 90 degree angle to each other as respects the contacting portion of the cam so that rotation of the cam imparts

successive incremental adjustments to the valves. A pump 75 constitutes a source of pressure supplying actuating medium to the conduit 76 which has a first branch conduit 77 controlled by the valve 65 in the valve bushing 77. A second branch conduit 78 extends to the valve casing 71. The position of the valve 70 determines the connection of the actuating medium to either conduit 79 or 80, these conduits extending to opposite ends of the in and out movement control cylinder 81 having intermediately disposed therein piston 82 on rod 83. Movements of the valve 70 will connect the pressure conduit 78 with one of the conduits 79 or 80 and will simultaneously connect the other of said pair of conduits with the general reservoir or return conduit system, thus determining the direction and extent of movement of piston 82.

A third branch pressure conduit 85 extends to the valve casing 74 and is coupled by valve 73 with either the conduit 86 or conduit 87. This pair of conduits extends to opposite ends of the cylinder 88 having intermediately disposed therein the piston 89 carried by piston rod 90.

As particularly illustrated in Figure 3, the spindle carrier 41 is provided with a first guide plate 91 having a slot 92 extending parallel with the longitudinal dimension of the carrier and adapted to receive the pin or connection 93 on the forward end of the piston rod 83. Due to this interconnection of the parts, any in or out movement imparted to the piston 82 will effect a corresponding movement of the carrier 41 as respects the slide 13 on which the cylinder 81 is fixed by bolts 94.

The carrier is provided with a second guide plate 95 having a slot 96 disposed at right angles to the direction of extent of slot 92 and having engaged in this guide slot the pin 97 carried by piston rod 90. Cylinder 88 is secured to the carrier 13 by bolts 98. Consequently, upon movement of the piston 89 in one direction or the other the cylinder will remain stationary while the connection between the piston rod 90 and the guide plate 95 will cause a transverse movement of the carrier 41 in a direction parallel to the face of the slide 13, the interengagement of pin 93 on piston rod 83 in the slot 92 permitting this relative sliding movement while the pin 93 restrains the spindle carrier against inward or outward movement. Correspondingly, when the piston 82 is actuated, the interengagement of pin 97 with guide plate 95 will permit free movement of the member 41 toward or from the carrier 13 while restraining the parts against any relative transverse movement.

From the foregoing it will be noted that there has been provided by the present invention an improved simplified contour grinding machine for accurate quantity production of contoured parts in accordance with the shape dictated by a pattern or master in which the tracer unit for control of movement of the machine is rigidly supported by the bed of the machine as is the power unit, while the power units for effecting the two directional movements of the grinding wheel spindles which jointly determine the orbital path of movement of the spindles with respect to the work piece as dictated by the pattern engagement of the tracer are supported by an indexible or feeding slide stationary on the column during contouring movements. By such construction the weight and mass of the movable parts under tracer control is minimized and reduced to a single spindle carrier supported for universal movement in a plane. It will further be noted that by the method of suspension employed, an extremely free movement of the spindle carrier is attained in that the major portion of the carrier weight is supported by the counterbalance 49 relegating to the toggles 33-37 and 34-38 substantially only the function of positionable maintenance of the carrier 41 in parallelism with the vertical slide 13, the carrier being substantially free floating on the pivot bearings for the toggles and doing away with frictional resistances attendant upon use of cross slides or the like, thus greatly increasing the sensitivity of the machine for slight variances in the resultant direction of movement of grinding wheel and work effected by the power shifters 82 and 89. As shown, each toggle link comprises an upper and spaced lower portion, said portions cooperating respectively with the upper and lower faces of the slide and carrier, maintaining the carrier in vertical parallelism with the slide.

It will further be noted that the main supporting or

vertical slide 13 is counterbalanced to facilitate its free incremental adjustment which may be effected by the pilot wheel 25 or suitable alternative conventional slide indexing mechanism. In the present instance, the slide 5 has been indicated as provided with the abutment 99 movable between the adjustable dogs 100 for limiting the vertical adjustments of the grinding wheels 46 with respect to the work pieces 47.

Particular attention is invited to the position and relationship of the pattern 60 as respects the produced work pieces 47 and their configuration. As illustrated in Figure 1, the cutters 46 are at an intermediate position axially or lengthwise of the work pieces 47 determining the axially transverse plane of contour engagement at the moment between the grinding wheels or cutters and the work pieces. Correspondingly, the tracer contactor 62 is shown at an intermediate point which determines the axially transverse plane of contour engagement utilized at that time between the tracer and pattern. It will be understood that as the slide 13 is raised, the cutters and the pattern will move upwardly with respect to the fixed tracer head unit and its tracer finger contactor at 62, while as the slide and the associated cutter carrier is moved downwardly the cutters 46 and contactor 62 will approach to the bases respectively of the work piece and the pattern. For effective reproduction, therefore, the pattern, which is shown as of tapered form, is mounted with its narrower end pointing downwardly, or phased 180 degrees as respects the position of the work piece.

By reference to Figures 6 and 7 representing respectively a horizontal section or section in an axially transverse plane of the pattern and of the work piece, it will be seen that the pieces are of symmetrical form but occupy positions on opposite hand or rotated through 180 degrees one with respect to the other. In other words, the concave surface 104 of the pattern controls reproduction of the corresponding surface 103 on the work, and the convex surface 102 on the pattern, the convex surface 101 on the work, and the thickened rounded end 106 serves as proper guide for a corresponding portion 105 on the work.

In ordinary 360 degrees contouring operations in which the pattern and work are supported as one unit and the tracer and cutters as a second unit, the pattern and work piece are correspondingly positioned. In the present instance, however, the pattern and cutters are mounted in a fixed relationship while the tracer and work pieces are likewise mounted in a fixed relationship although relative ambulatory movement is produced between the pattern-cutter pair and the work-tracer pair as well as a relative movement of the pairs in an axial direction. For proper production of the desired final contour on the work pieces 47 use is made of a pattern which is of opposite hand or rotatably phased 180 degrees with respect to the position of the work pieces. Considering Figures 6 and 7, if the carrier 41 is moving rearwardly, carrying with it the pattern 60, the reaction of the curved surface 104 against the tracer finger 62, pushing it to the left will activate the hydraulic control circuit to cause a movement of the pattern, the spindle carrier 41 and the cutters 46 toward the right, thereby producing the surface 103 on the work piece. Correspondingly, when the front corner of the pattern has traversed by the tracer, and the pattern is coming forward in engagement with the left hand side of the tracer finger contactor 62, the convexity of the pattern at 102 will initially react to cause a movement of the cutter carrier toward the left, producing the convex surface 101 on the work. It will thus be seen that, in effect, the relative movement between the cutter and work piece is equal in amount but 180 degrees phased in direction from that of the relative movement between the pattern 60 and tracer finger contact 62 and that the pattern must therefore be properly designed and mounted in correct phased relation to the work piece according to the particular contour to be reproduced.

It will further be noted that the work pieces are shown formed with a taper in an upwardly direction while the pattern is inverted to taper in a downward direction. By this relationship, as the slide 41 is adjusted toward or from the work support the relative movement of parts 60-62 and 46-47 will be equal but opposite so that the respective axially transverse planes of contour engagement between tracer and pattern on the one hand and cutter and work on

the other will correspond as to axially related dimensions either from base or apex of the pattern and work.

What is claimed is:

1. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide, a first power means interconnecting the slide and carrier actuatable for controlling their relative spacing, and a second power means interconnecting the slide and carrier and activatable to effect relative longitudinal movement of the slide and carrier.

2. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggle suspending the carrier on the slide, a first power means interconnecting the slide and carrier actuatable for controlling their relative spacing, a second power means interconnecting the slide and carrier and activatable to effect relative longitudinal movement of the slide and carrier, said first power means including a hydraulic motor supported on the slide having a reciprocating piston, a rod projecting from the piston in the direction of the carrier, and means on the carrier providing a longitudinal guideway, the piston rod having a portion interlocking with the guideway and reacting through said means on the carrier to effect in and out movement of the carrier.

3. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide, a first power means interconnecting the slide and carrier actuatable for controlling their relative spacing, a second power means interconnecting the slide and carrier and activatable to effect relative longitudinal movement of the slide and carrier, said power means for controlling the relative longitudinal movement of the slide and carrier comprising a hydraulic motor on the slide including a piston having a piston rod reciprocable in a direction parallel to the tie rod, means on the carrier providing ways extending at right angles to the direction of extent of the piston rod, and means on the rod interengaged with said ways for transmitting movements of the rod to the carrier.

4. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide for movement toward and from and for longitudinal movement parallel with the slide, a first power means interconnecting the slide

and carrier actuatable for controlling their relative spacing, a second power means interconnecting the slide and carrier and activatable to effect relative longitudinal movement of the slide and carrier, said first power means including a hydraulic motor supported on the slide having a reciprocating piston, a rod projecting from the piston in the direction of the carrier, means on the carrier providing a longitudinal guideway, the piston rod having a portion interlocking with the guideway and reacting through said means on the carrier to effect in and out movement of the carrier, and said power means for controlling the relative longitudinal movement of the slide and carrier comprising a hydraulic motor on the slide including a piston having a piston rod reciprocable in a direction parallel to the tie rod, means on the carrier providing ways extending at right angles to the direction of extent of the piston rod, and means on the rod interengaged with said ways for transmitting movements of the rod to the carrier.

5. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide for movement toward and from and for longitudinal movement parallel with the slide, a first power means interconnecting the slide and carrier actuatable for controlling their relative spacing, a second power means interconnecting the slide and carrier and activatable to effect relative transverse movement of the slide and carrier, said first power means including a hydraulic motor supported on the slide having a reciprocating piston, a rod projecting from the piston in the direction of the carrier, means on the carrier providing a longitudinal guideway, the piston rod having a portion interlocking with the guideway and reacting through said means on the carrier to effect in and out movement of the carrier, and said power means for controlling the relative longitudinal movement of the slide and carrier comprising a hydraulic motor on the slide including a piston having a piston rod reciprocable in a direction parallel to the tie rod, means on the carrier providing ways extending at right angles to the direction of extent of the piston rod, and means on the rod interengaged with said ways for transmitting movements of the rod to the carrier, a pattern supported on the spindle carrier, and a contouring tracer control mechanism carried by the bed adjacent the work supporting portion of the bed, said mechanism including a control finger extending in the direction of the pattern support for actuation by a pattern on the support automatically to control the directional movements of the spindle carrier.

6. A contour grinding machine including a bed having a work supporting portion, a column rising from the bed, a slide mounted on the column for movement toward and from the bed, a spindle carrier, a parallel motion connection between the slide and the spindle carrier including spaced toggle mechanisms each including a link pivoted to the carrier, a link pivoted to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide, a first means connecting the slide and carrier to maintain them in spaced relation while permitting their relative longitudinal movement, and a second means connecting the slide and carrier to prevent their longitudinal movement while permitting their relative toward and from movement, and a power device for adjusting one of said means to vary the relative positions of the slide and carrier.

7. A contour grinding machine including a bed having a work supporting portion, a column rising from the bed, a slide mounted on the column for movement toward and from the bed, a spindle carrier, a parallel motion connection between the slide and the spindle carrier including spaced toggle mechanisms each including a

link pivotal to the carrier, a link pivotal to the slide, means pivotally connecting the links of each toggle, the links pivoted to the carrier being parallel and the links pivoted to the slide being parallel, and a tie rod joining the connecting pivots of the respective toggles for maintaining same in prescribed relation one to the other, said toggles suspending the carrier on the slide, a first means connecting the slide and carrier to maintain them in spaced relation while permitting their relative longitudinal movement, and a second means connecting the slide and carrier to prevent their longitudinal movement while permitting their relative toward and from movement, a first power device for adjusting one of said means, a second power device for adjusting the other of said means, and a common controller for determining the actuation of both power devices to establish the resultant direction of movement of the toggle suspended carrier with respect to the slide.

8. A contour grinding machine including a bed having a work supporting portion, a column rising from the bed, a slide mounted on the column for movement toward and from the bed, a spindle carrier, a parallel motion connection between the slide and the spindle carrier including spaced toggle mechanisms each including a link pivoted to the carrier, a link pivoted to the slide, means pivotally connecting the links of each toggle, the links pivoted to the carrier being parallel and the links pivoted to the slide being parallel, and a tie rod joining the connecting pivots of the respective toggles for maintaining same in prescribed relation one to the other, said toggles suspending the carrier on the slide, a first means connecting the slide and carrier to maintain them in spaced relation while permitting their relative longitudinal movement, and a second means connecting the slide and carrier to prevent their longitudinal movement while permitting their relative toward and from movement, a first power device for adjusting one of said means, a second power device for adjusting the other of said means, and a common controller for determining the actuation of both power devices to establish the resultant direction of movement of the toggle suspended carrier with respect to the slide, said controller including a tracer unit car-

ried by the bed having a pattern contactor finger projecting toward the carrier for actuation by a pattern on the carrier, automatically to establish said resultant direction of movement.

5. 9. A contour grinding machine including a bed having a work supporting portion, a column rising from the bed, a slide mounted on the column for movement toward and from the bed, a spindle carrier, a parallel motion connection between the slide and the spindle carrier comprising spaced toggle mechanisms each including a link pivotal to the carrier, a link pivotal to the slide, means pivotally connecting the links of each toggle, the links pivoted to the carrier being parallel and the links pivoted to the slide being parallel and a tie rod joining the connecting pivots of the respective toggles for maintaining same in prescribed relation one to the other, said toggles suspending the carrier on the slide, a first power means interconnecting the slide and carrier actuatable for controlling their relative spacing, a second power means interconnecting the slide and carrier and activatable to effect relative longitudinal movement of the slide and carrier, and means supporting said slide and carrier for movement relative to the column, said means comprising a flexible cable, a counterweight intermediately suspended on the cable, pulleys carried by the column and supporting the cable, means connecting one end of the cable to the slide, and means connecting the other end of the cable to the carrier.
